UNITED STATES PATENT OFFICE.

ADOLPH GOHL, OF CHICAGO, ILLINOIS, ASSIGNOR TO THE LAMON-GOHL COMPANY, OF CHICAGO, ILLINOIS, A CORPORATION OF ILLINOIS.

DESIGN FOR A GLASS JAR.

54,614.

Specification for Design.

Patented Mar. 9, 1920.

Application filed August 11, 1919. Serial No. 316,881. Term of patent 14 years.

To all whom it may concern:

Be it known that I, ADOLPH GOHL, a citizen of the United States, residing at Chicago, in the county of Cook and State of Illinois, have invented a new, original, and ornamental Design for a Glass Jar, of which the following is a specification, reference being had to the accompanying drawing, forming part thereof.

In the drawings,

Figure 1 is a side elevational view of a glass jar embodying my new design.

Fig. 2 is a view of the bottom of said jar.

Fig. 3 is a perspective view of the jar as seen through the upper open end of the same, and

Fig. 4 is a vertical sectional view of said jar.

I claim:

The ornamental design for a glass jar, as shown.

In witness whereof, I hereunto subscribe my name this 7 day of August, 1919.

ADOLPH GOHL.
